(57) **CLAIM**

The ornamental design for a multi-compartment compact, as shown and described.

DESCRIPTION

FIG. 1 is a front perspective view illustrating my design for a multi-compartment compact shown in a closed orientation; FIG. 2 is a front perspective view thereof shown in a partially open orientation;

FIG. 3 is a front perspective view thereof shown in a fully open orientation;

FIG. 4 is a front elevation view thereof shown in a closed orientation;

FIG. 5 is a front elevation view thereof shown in a partially open orientation;

FIG. 6 is a right side elevation view thereof shown in a closed orientation; and

FIG. 7 is a right side elevation view thereof shown in a partially open orientation;

FIG. 8 is a right side elevation view thereof shown in a fully open orientation;

FIG. 9 is a left side elevation view thereof shown in a closed orientation;

FIG. 10 is a left side elevation view thereof shown in a partially open orientation;

FIG. 11 is a left side elevation view thereof shown in a fully open orientation;

FIG. 12 is a back side elevation view thereof shown in a closed orientation;

FIG. 13 is a back side elevation view thereof shown in a partially open orientation;

FIG. 14 is a top plan view thereof shown in a closed orientation;

FIG. 15 is a top plan view thereof shown in a partially open orientation;

FIG. 16 is a top plan view thereof shown in a fully open orientation;

FIG. 17 is a bottom plan view thereof shown in a closed orientation;

FIG. 18 is a bottom plan view thereof shown in a partially open orientation; and,

FIG. 19 is a bottom plan view thereof shown in a fully open orientation.
